UNITED STATES PATENT OFFICE

CHARLES B. KENNEDYE, OF UNIVERSITY CITY, MISSOURI, ASSIGNOR TO THE KENNEDYE CORPORATION, OF WILMINGTON, DELAWARE, A CORPORATION OF DELAWARE

REAMER BLADE

Application filed March 3, 1927. Serial No. 172,247.

The present improvements relate more particularly to a reamer blade of the type adapted to have removable engagement with a suitable supporting head.

5 The device of the present invention is particularly adaptable for use with well-drilling machinery of the rotary type and comprises various essential features of high utility and obvious advantage.

10 More specifically the reamer blade of the present invention comprises a supporting body adapted to have cooperative removable engagement with a suitable supporting head, from two sides of which body portion 15 project reaming or drilling surfaces. One of the latter comprises a portion projecting beyond the side wall of the head presenting an elongated reaming edge or edges lying in an axis substantially parallel to the plane of the 20 head. From an adjacent lower edge of the supporting body portion projects a cutting blade having a cutting surface.

The device of the present invention may be used in combination with a drilling bit which 25 forms the subject matter of a co-pending application Serial No. 172,248, filed March 3, 1927.

The use of the reamer blade of the present invention, due to the elongated reaming edge 30 or edges, results in the actual drilling of a much straighter hole and one which is true to gauge. The device is characterized by its economy in cost of manufacture and the ease with which it may be installed in or removed 35 from a suitable supporting head.

In use and operation, two or more of these reamer blades are used with each head, the reamer blades being suitably spaced apart. In drilling practice it has been found that by 40 presenting transversely spaced reaming surfaces to the formation being drilled that, relative to the speed of rotation, the spaced elongated reaming surfaces will function if the supporting members drill at an angle 45 when hard formation is suddenly encountered.

The utility of the invention, the objects thereof and advantages accruing to its use will be more apparent from the following description.

In the drawings, Fig. 1 is a face elevational view; Fig. 2 is an end elevational view; and Fig. 3 is a bottom end view of the reamer blade of the present invention; Fig. 4 is a cross sectional view taken on line 4—4 of 55 Fig. 2.

Referring more particularly to the drawings; 1 designates the supporting stock or body portion of the reamer blade, which in the present instance takes substantially the form of an elongated rectangle having upper edge 2, side edges 3 and 4, and lower edge 5. This supporting body 1 is constructed of any suitable material and may be of cast, forged, or rolled steel. The illustration in 60 the drawings is full size for drilling an 11 inch hole. It is to be understood, of course, that changes may be made in the proportions, in thickness, length, or width without departing from the scope of the present invention. This supporting body 1 is scientifically heat-treated to secure the most efficient results. The sides 2 and 3 are preferably rounded as indicated in the drawings in order to provide greater and more efficient 65 bearing surfaces when in place in a suitable supporting head.

The reamer blade illustrated in the drawings is adapted to have cooperative removable locking engagement with a suitable 70 form of supporting head. One manner in which the reamer blade per se may have locking engagement with a head may comprise the locking lug 5 which is adapted to register with a corresponding longitudinal 75 groove in said supporting head. When the reamer blade is forged, the formation of the locking lug 5 will result in a recess 6 on its opposite side. It is obvious, of course, that any other form of locking arrangement may be provided and I do not wish to limit myself to the lug 5 and recess 6.

Referring now to one of the features of the present invention, the side 4 is the one which projects beyond the sides of the head and as indicated clearly in Fig. 4, this is provided with a knife-like cutting edge 7, which tapers rearwardly or inwardly to provide clearance and permit relief for said cutting edge 7, and a similar cutting edge 8 spaced from the

cutting edge 7 by means of the longitudinal recess 9. It is to be noted that the knife-like edge 8 lies in a plane rearwardly and inwardly relative to the original plane of the edge 7, but in explanation it is to be noted that the edge 8 is in the same circular plane. The surface projects rearwardly and inwardly rather sharply from the point 8 as indicated at 10 to provide clearance similar to that permitted for the cutting edge 7. In operation it is the elongated reaming side 4 which is presented to the formation being drilled and it assists in the drilling of a straighter hole by keeping the head true to gauge and properly supported. The advantage of providing two or more sharp, knife-like edges 7 and 8 on this reaming side surface is that it permits faster reaming, cooling water being permitted to flow up through the longitudinal recess 9 and the sharp, knife-like edges will cut more freely and with less resistance, than one edge.

Now describing another feature of the present invention, projecting from the base 25 of the supporting structure 1 is the cutting blade 11 which in the present instance tapers inwardly from the side 3 of the supporting structure along the line 12 to present a cutting surface 13 of less width than the width of the 30 supporting structure 1. The lower edge 5' of the supporting structure 1 may be formed on a taper from the rounded side 3 to the side 4 as indicated clearly in Fig. 1. The cutting blade 11 from this point downwardly is 35 decreased in thickness both on its front and rear surfaces as indicated clearly in Fig. 3, thus it is to be noted that the cutting edge 13 is of materially less width and thickness than the supporting structure 1 and is of course, of 40 relatively short length.

As heretofore pointed out the reamer blade of the present invention may be utilized as a reamer blade, and at the same time as a drilling cutter in combination with a drilling 45 bit such as illustrated in my co-pending application, Serial Number 172,248, filed March 3, 1927.

One advantage of the particular construction of the blade 11 and the reasons underlying the tapering of the lower edge 5' may be explained as follows: The material removed in the drilling operation must not be permitted to clog up in any pockets between the head and reamer and to facilitate the passage 55 of said material, the lower edge 5' has been tapered as indicated. This tapering and the reduction in thickness of the blade will assist in the removal of any such material.

60 By the term "supporting structure" as used in the specification, I intend to indicate the structure designated as 1, which is adapted to be substantially wholly mounted within a head with only a portion of the side 4 and 65 the blade 11 projecting from the side and

base respectively. By the expression "elongated reaming side", I intend to indicate the side 4. By the expression "blade" used alone, I intend to indicate the drilling blade 11 projecting from the base of the support 1. It is to be pointed out that the reamer blade is of greater length than width and of greater width than thickness. I have illustrated the ribs 5 as being rounded in surface contour and as having a rounded upper edge. The 75 lower end may be cut away inwardly relative to the longitudinal plane thereof as indicated at 14 for the purpose of cooperatively engaging with the rounded top edge of a drilling bit when the reamer is used in the combination as heretofore described.

It is to be noted that the cutting edge 13 is offset at an angle different from the general longitudinal plane of the supporting body 1 in order to assist in the discharge or removal 85 of material as it is being removed in drilling, the angle being so arranged that the material is directed outwardly and upwardly away from the cutting medium.

I claim as my invention:

1. A reamer blade consisting essentially of a supporting body of greater length than width and of greater width than thickness, one side of which comprises an elongated reaming means adapted to be presented to the formation being drilled and consisting of a plurality of longitudinal relatively thin spaced cutting edges, a cutting blade projecting from the lower edge thereof of substantially less width, length and thickness than the supporting body and so disposed as to form an offset shoulder on the entire lower edge of said supporting body, and an integral locking lug projecting from one face of the supporting body intermediate opposite longitudinal edges, said locking lug lying in a plane substantially parallel to said longitudinal edges.

2. A reamer blade consisting essentially of a supporting body substantially rectangular in configuration, having two adjacent rounded edges, a third edge provided with a plurality of longitudinal relatively thin cutting edges, and a lower edge provided with an off-set shoulder and an integral cutting blade having a lower cutting edge and a side cutting edge forming an uninterrupted continuation of said third side of the supporting body, the opposite edge of said cutting blade tapering from one side of the supporting body inwardly and downwardly to provide a cutting edge of considerably less width than the supporting body.

CHARLES B. KENNEDYE.
